ELECTROMECHANICAL REPRODUCER FOR
GUNFIRE

André Valentin Baranoff, Saint-Mande, France

Application December 13, 1932, Serial No. 647,069
In France December 14, 1931

1 Claim. (Cl. 35—25)

This invention relates to apparatus designed for use in military and naval colleges for the instruction of the personnel usually employed in the handling of artillery.

5 The main object of the invention is to provide instruction apparatus of this character, in which the trajectories of moving targets can be reproduced in miniature, and in which the exact position of such targets may be continuously determined from a miniature reproduction of the terrain under consideration.

Other objects of the invention will become apparent as the detailed description thereof proceeds.

15 In the drawing:

Fig. 1 is a perspective view of a preferred form of the invention;

Fig. 2 is a plan of the apparatus illustrated in Fig. 1; and

20 Fig. 3 is a fragmentary perspective view of part of the apparatus illustrated in Figs. 1 and 2.

As shown in the drawing, the invention comprises a table having a substantially horizontal flat table top T, suitably secured to and supported by the legs L1, L2 and L3. The top T is provided with a rear wall W, having a straight upper edge designed to represent the horizon. Sides S1 and S2 are connected at their rear ends to the opposite ends of the rear wall W; and, are continued forwardly to form the semi-circular front wall S3.

The sides S1, S2 and S3 form, with the rear wall W, a container adapted to receive water, or other liquid, up to the level of the horizon edge W1; and the top T is provided with any desired number of valve controlled drain pipes d, to empty the container when it is desired to make use of it for any other purpose, such as supporting the relief map shown in Fig. 3.

40 The center of the semi-circular wall S3 is provided with an aperture x, through which projects a rod 3 having a stud s which may serve as an indicator of target position over the terrain map, or may be used as a pivotal support for a miniature target 6, shown in Figs. 1 and 2. The other end of the rod 3 is suitably secured to the slide 4 which is slidably mounted on the upper face of the beam 1. The beam 1 projects laterally from a fitting f suitably secured to the shaft 2 which is journaled to rotate about a vertical axis in the center of the semi-circular wall S3.

The slide 4 extends down along one side of the beam 1; and, this downward extension is 55 internally screw-threaded to receive the screw-

threaded rod 10, having its opposite ends mounted to rotate in the gear casings c and c' at the opposite ends of the beam 1. A handwheel 5, connected to suitable gearing in the gear case c, effects rotation of the rod 10 and thereby moves 5 the rod 3 radially of the semi-circular wall S3.

A hand wheel 7 is geared to one end of the shaft sh to rotate the same; and, a bearing bracket bb serves as a journal for the other end of the said shaft sh. A bevel gear bp on the end 10 of the shaft, meshes with the bevel rack br on a shelf bracket secured to the leg L1. The rotation of the handwheel 7 may therefore effect rotation of the beam 1 and rod 3 about the axis of the vertical pivot 2 simultaneously with the 15 lengthwise movement of the rod 3 over the top T. In this manner, the indicator s or target 6, may be moved to any desired position over the top T.

A directing table, designated generally by the reference character P, is arranged symmetrically 20 below the beam 1, when the beam is normal to the arcuate rim S3. This table P comprises two vertically spaced apart plates p and pl, the lower plate p having a roughened surface and the upper plate pl being formed of ground glass. A 25 small carriage 11, having an electric lamp mounted therein, is supported on the plate p by rubber covered wheels 11' and 11'' for movement under the plate pl.

A screw threaded rod 12 engages an internally 30 screw-threaded aperture in the carriage 11 and is journaled at one end in a slide 13 mounted to slide lengthwise of a guide 14 fixed to the upper plate pl. A handwheel 15 rotates the rod 12 to move the carriage 11 to any desired position under the plate pl. This movement, combined with the sliding movement on the guide 14, enables the operator to move the carriage 11 to any desired position under the plate pl; and, to follow any given path pa which may be marked 35 on the plate pl.

The directing table P may be displaced in two directions on the base Ba along the guides 19 and 20, the guide 19 being fixed to the base, and the guide 20 being movable transversely of the 45 guide 19. Three controlling handwheels 21, in cooperation with racks and screws (not shown) serve to effect these movements of the directing table P.

In order to cause the target indicator 6 to follow the movements of the carriage 11, to an enlarged scale, a second screw-threaded rod is journaled at its opposite ends to the beam 1; and the end thereof nearer the gear case c', is connected by gearing to the adjacent end of the rod 55

10 so as to effect rotation of the rod 9 at a speed having any desired ratio to the speed of rotation of the rod 10. A 45 degree prism 8 is secured to an internally screw-threaded fitting 8' meshing with the rod 9; and, the shaft *sh*, passing through a bore in said fitting 8', prevents rotation of the prism 8 about the axis of the rod 9. Another 45 degree prism 17 at the control end of the beam 1, cooperates with the prism 8 to deflect the rays of light emanating from the lamp in carriage 11 into position for convenient observation by the control operator.

It will be apparent that an operator at the outer end of the beam 1, can manipulate the control hand wheels 5 and 7 to move the prism 8 to duplicate in space the movements of the carriage 11; as, for example, along the path *pa* plotted on the ground glass plate *pl*. In so moving the prism 8, the operator moves the target indicator 6 to a corresponding position over the relief map, or other terrain representation, which is properly located on the table T; thereby giving information to the batteries as to the nature of the terrain represented directly under the target indicator. In the case of a target in motion the target indicator 6 may be rotated on the stud 2, by means of the handwheel 18, to indicate the direction of such motion.

It will be evident that the apparatus described constitutes, in effect, a light-ray pantographic structure, which may be constructed to duplicate, in any desired ratio, the movements of a target plotted on the plate *pl*, over any relief scale map, or other scaled representation of the terrain within firing range of guns located in known or determinable positions relative to the apparatus. Loop straps *str* are secured in pairs on the sides of the horizontal table T, to form supporting members in which may be detachably mounted the inner ends of brackets supporting miniature guns in positions corresponding to the locations of real guns relative to the terrain under fire. 15

What I claim is:—

In fire control apparatus: a substantially horizontal table adapted to support a miniature scale representation of terrain within firing range of guns located in known or determinable positions relative to said table; a supporting beam rotatable about a vertical axis on said table; a rod having an indicator on one end thereof and mounted to rotate with and slide axially on said beam; and means on said beam for rotating the latter and 25 means for sliding said rod on said beam.

ANDRÉ VALENTIN BARANOFF.
